CLAIM

The ornamental design for a visor for automatic teller machine, as shown and described.

DESCRIPTION

FIG. 1 is a front view of a visor for an automatic teller machine showing our new design;
 FIG. 2 is a rear view thereof;
 FIG. 3 is a left side view thereof;
 FIG. 4 is a right side view thereof;
 FIG. 5 is a top plan view thereof;
 FIG. 6 is a bottom plan view thereof;
 FIG. 7 is a front right perspective view thereof; and,
 FIG. 8 is a front right perspective view thereof attached to an automatic teller machine.

The broken lines in the drawing views are included to show unclaimed subject matter only and form no part of the claimed design.
